Primary Examiner — Cathron Brooks*Assistant Examiner* — Andrew Nemeth(74) *Attorney, Agent, or Firm* — Kilpatrick Townsend & Stockton LLP(57) **CLAIM**

The ornamental design for the display screen or portion thereof with graphical user interface, as shown and described.

DESCRIPTION

FIG. 1 is a front view of a display screen or portion thereof with graphical user interface showing my new design; and, FIG. 2 is an alternative embodiment thereof.

The broken line showing of the display screen or portion thereof forms no part of the claimed design.

1 Claim, 2 Drawing Sheets(56)
